Specification for Design.

Patented Oct. 18, 1921.

Application filed January 3, 1919. Serial No. 269,540. Term of patent 14 years.

To all whom it may concern:

Be it known that we, LUCIUS L. CAILLET, of Riverside, in the county of Riverside and State of California, and CLYDE C. CAILLET, of Johnstown, in the county of Boulder and State of Colorado, citizens of the United States of America, have invented a new, original, and ornamental Design for Rivet-Punches, of which the following is a specification, reference being had to the accompanying drawings, forming part thereof.

The figure is a perspective view of a rivet punch showing our new design.

We claim:

The ornamental design for a rivet punch, as shown.

LUCIUS L. CAILLET.
